UNITED STATES PATENT OFFICE.

JOSHUA TEDFORD, OF CHICAGO, ILLINOIS.

GARMENT FORM.

Application filed June 8, 1921. Serial No. 475,907.

To all whom it may concern:

Be it known that I, JOSHUA TEDFORD, a citizen of the United States, and resident of Chicago, in the county of Cook and State 5 of Illinois, have invented certain new and useful Improvements in Garment Forms, of which the following is a specification.

This invention relates to garment forms and more particularly to a form especially 10 adapted for use in coat sleeves.

In preparing coats for display purposes, it is the practice to stuff the sleeves with crumpled tissue paper to give them the desired form. This practice is, however, possessed of numerous disadvantages, among 15 which is the fact that the tissue paper does not stay in place and must be inserted after the coat is placed in its final position in the display window. Also, the tissue paper 20 bulges the sleeves at various points and does not effectively prevent the sleeves from wrinkling.

Therefore, an important object of this invention is to provide a sleeve form which 25 may be readily and conveniently inserted in a sleeve to give the sleeve the desired fullness both at its front and rear sides and which will also prevent the adjacent portion of the coat from wrinkling.

Further, the invention aims to provide a 30 sleeve form having an exterior surface which is somewhat rough whereby the form will remain in an adjusted position in the sleeve.

A further object of the invention is to 35 provide a sleeve form which may be inserted into the sleeves of coats after being pressed so as to prevent the coat from drying in a wrinkled condition.

The invention forming the subject matter 40 of this application also aims to provide a form for coats capable of use when draping coats on display stands or pedestals to give the upper portion of the sleeve and the adjacent portions of the coat the desired fullness.

Other objects and advantages of the 45 invention will be apparent during the course of the following description.

In the accompanying drawing forming a 50 part of this application and in which like numerals are employed to designate like parts throughout the same,

Figure 1 is a perspective view of a pair 55 of the improved sleeve forms applied to a coat form.

Figure 2 is an edge elevation of the sleeve form applied, the portion of the coat shown being in section.

Figure 3 is a perspective of one of the 60 sleeve forms.

Figure 4 is a central vertical longitudinal 65 sectional view through the form.

Figure 5 is a perspective of a modified form of the invention applied.

Figure 6 is an edge elevation of the same applied, the same being shown extended into the sleeve of a coat.

Figure 7 is a perspective of the form illustrated in Figures 5 and 6.

Figure 8 is a perspective of the form illustrated in Figure 7, the view illustrating the opposite side of the form.

Figure 9 is a longitudinal sectional view 70 through the form.

In the drawing the numeral 10 designates a coat form ordinarily used for the purpose of supporting coats on display, the said form being mounted upon a base 11.

The invention consists of a pair of sleeves 80 12 formed from an elongated body of felt or other suitable material 13. In manufacture the body of felt is preferably about one-half inch thick and has connection with a second layer of felt 14 by means of stitching. As illustrated in Figure 4 the second 85 layer of felt 14 is located at the sleeve head and in addition to providing the rear portion of the sleeve form with the desired stoutness also assists in giving the sleeve the 90 necessary shape.

The stitching which connects the outer layer 14 to the body 13 also connects a binding strip 16 to the upper portion of the form so as to enclose the upper end portion of the 95 felt body and to form a gradually reduced lip which overhangs the shoulder. With reference to Figure 4 it will be observed that the upper end of the body 13 is gradually reduced in thickness so that that portion of 100 the sleeve form which overhangs the shoulder will be tapered transversely. By reason of this construction the coat 18 which is applied to the form will be snugly fitted about the shoulder of the form and the sleeve 105 head.

A covering of felt 20 is applied to the body 13 and has its exterior surface roughened so that when positioned within the coat sleeve 21 the form will remain in position. 110 The upper portion of the covering 20 which is applied to opposite sides of the body is

secured to the body by the same stitching which connects the binding strip 16 to the body. The covering 20 is also secured along its edges to the edges of the body by means 5 of stitching.

The sleeve head is given the curved formation illustrated in Figure 2 by wetting the form and subsequently shrinking the inside and stretching the outside. The form 10 may now be pressed so that it will retain the desired shape.

The sleeve form is provided at its intermediate portion or slightly in advance of its head with a pair of oppositely arranged 15 flaps or wings 25 which are adapted to be folded inwardly as illustrated in Fig. 2 to contact with the inner side of the sleeve at the elbow portion of the same for the purpose of applying a uniform and evenly distributed pressure to the sleeve. In preparing the improved sleeve form for use the wings 25 which are of rectangular formation are pressed perfectly flat with the adjacent portion of the body and when folded 20 inwardly will exert a constant outward pressure and thereby display the lines of the coat sleeve to the greatest advantage.

In order that the sleeve form might be readily inserted into a sleeve I have provided 30 the same at its forward portion with a pocket 28 adapted for the reception of the hand whereby the operator may readily insert the form into the sleeve and subsequently adjust the same therein. This pocket is 35 on the inner side of the form and therefore does not cause the adjacent portion of the coat sleeve to bulge at this point.

A pair of the sleeve forms is employed for each coat and the same are connected by 40 means of a flexible strip 30 of any suitable material. In practice the tape may be of a length to extend across the back of the form in the manner illustrated in Figure 1.

With reference to Figures 2 and 3 and 45 Figure 4 it will be seen that the longitudinal edge portions of the body are curved transversely so that the same provide mild creases at the front and rear sides of the sleeve.

50 In the form of the invention illustrated in Figures 5 to 9 inclusive the form generally designated by the numeral 32 is especially adapted for use in connection with pedestals or stands 33. In use the form 32 is applied to the hanger 34 and a coat is draped over the form and the hanger. Of course in draping the coat it is not snugly 55 fitted to the form but the upper portion of the same is properly positioned on the hanger 34 and the form 32 and the lower portion of the coat and the lower portion of the sleeves are allowed to rest upon the plateau upon which the pedestal or stand 33 is mounted.

60 As illustrated in Figure 9 the form 32 is

composed of a body of felt 35 enclosed within a covering 36 of a felt of a different quality. The edges of the felt covering 36 are secured to the edges of the body by means of stitching or the like. The shoulder portion is rounded by means of additional pieces of felt 37 applied to the inner side of the body and by a transversely extending strip of tape 38, the said strip of tape and the additional layer of felt being securely 75 attached to the body by means of stitching.

Intermediate the ends of the form the same is provided with lateral extensions or wings 40 which embrace the back and breast portions of the coat so as to support the same in the desired position. In carrying out the invention the upper end portion of the form is tapered to a point and is provided with a loop 41 by means of which the form may be secured in the proper position 85 with relation to the hanger and with relation to the coat sleeve. A sleeve form constructed in accordance with the foregoing description and the accompanying drawing dispenses with the necessity of stuffing paper 90 in the sleeves and also permits the lines of a coat to be effectively displayed.

Also a considerable saving in labor is brought about since it requires but several minutes to insert a form in a coat, whereas 95 it requires considerably longer to properly stuff the sleeve with tissue paper.

I claim:—

1. A sleeve form comprising an elongated body of yieldable material having its edge 100 portions formed with wings.

2. A sleeve form comprising an elongated body of yieldable material having its intermediate portion formed with wings, and a flexible element connected to the upper portion 105 of said body.

3. A sleeve form for coats comprising a body of yieldable material provided intermediate its ends with laterally projecting wings, said body being provided at its upper 110 portion with a shoulder engaging attaching head.

4. A sleeve form for coats comprising a body formed with a rounded head adapted for overhanging a portion of a support, and 115 wings secured to said body in advance of said head and adapted to contact with the inner side of a sleeve whereby to maintain the sleeve in its full position.

5. A sleeve form for coats comprising an 120 elongated body having its rear portion formed with a rounded lip gradually reduced in thickness toward its free edge to form an attaching means for the form.

6. A sleeve form for coats comprising an 125 elongated body having its rear portion formed with a rounded lip gradually reduced in thickness toward its free edge to form an attaching means for the form, and wings associated with said body.

7. A sleeve form comprising an elongated body of yieldable material having its forward portion provided with a pocket adapted for the reception of the hand whereby the body may be inserted into and adjusted in a sleeve.

8. A sleeve form comprising a transversely curved elongated body of yieldable material having its forward portion provided with a pocket adapted for the reception of the hand whereby the body may be inserted into and adjusted in a sleeve, the said pocket being on the inner side of said body.

9. A sleeve form for coats comprising an elongated body of felt having its rear por-

tion rounded and tapered to form a head adapted to overhang the shoulder of a coat form, and a strip of binding secured to opposite sides of said head, the forward portion of said body being formed with a pocket ²⁰ adapted for the reception of the hand.

10. A form comprising a pair of elongated bodies having their forward portions provided with means whereby the same may be inserted into the sleeves of a coat, ²⁵ and a flexible element connecting said bodies and constituting a means to limit the forward movement of the bodies.

JOSHUA TEDFORD.
